UNITED STATES PATENT OFFICE.

HENRY E. LONGWELL, OF PITTSBURG, AND FRANCIS HODGKINSON, OF EDGEWOOD PARK, PENNSYLVANIA, ASSIGNORS TO THE WESTINGHOUSE MACHINE COMPANY, A CORPORATION OF PENNSYLVANIA.

PACKING.

No. 813,723.

Specification of Letters Patent.

Patented Feb. 27, 1906.

Application filed November 21, 1903. Renewed November 23, 1904. Serial No. 234,008.

To all whom it may concern:

Be it known that we, HENRY E. LONGWELL, a citizen of the United States, residing at Pittsburgh, and FRANCIS HODGKINSON, a subject of the King of Great Britain and Ireland, residing at Edgewood Park, in the county of Allegheny and State of Pennsylvania, have invented a new and useful Improvement in Packings, of which the following is a specification.

Our invention relates to packings for rotary shafts; and it has for its object to provide such a packing which shall effectively withstand considerable differences in fluid-pressure at its respective sides without materially interfering with the rotative movement.

With this end in view we have devised a liquid packing which is or may be of general application to rotating shafts, but is here illustrated and specifically described as utilized in connection with the shaft of a steam-turbine. This illustration and description is not intended to be restrictive, since the invention is obviously of more general application.

In the accompanying drawings, Figure 1 is a longitudinal section of a portion of a fluid-pressure turbine and our packing device for its shaft, portions of the shaft and fluid-supply pipes being broken away. Fig. 2 is a vertical transverse section on line II II of Fig. 1.

There is usually a very considerable difference between the fluid-pressure in the interior and that at the exterior of the casing of a fluid-pressure turbine, and in consequence there is a strong tendency for the escape of steam around or through the shaft-bearing in case the internal pressure exceeds the external pressure or an inflow of air in case the external pressure exceeds the internal pressure. Our invention is designed to effectively prevent the leakage of fluid-pressure in either direction and embodies certain features of construction, which will be now described.

The casing 1 of the turbine, which is provided with a series of guide-vanes 2, contains a rotary drum 3, having a series of blades or buckets 4, mounted upon a shaft 5, one of the bearings for which comprises a box or housing 6, the inner end 7 of which constitutes an integral part of the casing and the outer end or

head 8 of which is removably bolted in position. Mounted rigidly upon the shaft 5 and centrally within the box or housing 6 is a 55 disk 9, the diameter of which is slightly less than the internal diameter of the housing, so as to provide a clearance-space 10. The disk 9 is also provided with a central circumferential groove 11, and each of its end faces is provided with radial blades or wings 12, between the outer edges of which and the corresponding end walls of the housing is also a small clearance-space 13. A suitable liquid—such, for example, as water or oil—is supplied centrally to the bottom of the housing by means of a pipe 14, containing a suitable valve 15. The liquid or air, or both, may be expelled from the housing-chamber through a pipe 16, in which is located a relief-valve 17, that is 70 normally held to its seat by means of a spring 18, the pressure exerted by the spring being susceptible of adjustment by means of a screw 19.

Instead of employing the means shown for regulating the fluid-pressure the pipe 16 and its valve 17 might be omitted and the valve 15 in the supply-pipe 14 be so designed and constructed as to automatically regulate the pressure supplied to the chamber 6, or the 80 liquid might be supplied from a tank, the elevation of which would be such that gravity would exert the desired uniform pressure.

The disk 9, with its vanes 12, is, in fact, a double centrifugal pump. As an example of 85 its operation it may be assumed that it would pump to thirty pounds per square inch if furnished with a supply of liquid without head at the axis. In such a case we would so load the relief-valve that it would become unseated at a pressure of twenty pounds per square inch. It would then follow that if the fluid were fed to the chamber through the pipe 14 a pressure of twenty pounds per square inch would be maintained at the periphery of the 90 centrifugal pump, since the pressure is maintained at this value by the relief-valve. We would therefore have an annulus of fluid in the outer part of the casing 6 at a pressure of twenty pounds per square inch, which would 100 prevent the passage of any gas of a lesser pressure than the twenty pounds per square inch, as above stated, either from within the turbine to the outside, or vice versa. Such an

example as that just cited would be suitable for an apparatus designed to pack against either an internal or an external pressure of about fifteen pounds per square inch. Should it be necessary to pack against greater pressures, a pump designed to pump to a greater head than the thirty pounds per square inch above stated would obviously be employed. The quantity of liquid necessary for the operation of this apparatus is only such as will serve to carry away the heat to a sufficient extent to avoid vaporization.

The specific details of construction may obviously be varied within comparatively wide limits from what is shown, it being obviously feasible to employ pumping apparatus having a plurality of rotary members or a single disk of different form and dimensions, either with or without lateral wings or blades or with them on only one end, or to otherwise vary the details. It would also be feasible under some circumstances to employ a constant body of liquid for packing purposes, the flow of liquid through the packing-chamber being necessary only where the temperature is so high as to volatilize the liquid if it is not renewed either continuously or at frequent intervals.

We claim as our invention—

30 1. The combination with a rotatable shaft having a circumferential projection, of a cylindrical chamber for said projection and a body of packing liquid partially filling said chamber and retained in the outer portion thereof by the rotation of said projection.

2. The combination with a rotatable shaft having a circumferential projection and a bearing-box having a cylindrical chamber of greater diameter than said projection and in 40 which said projection is concentrically located and a body of packing liquid which partially fills said chamber and is retained in the outer portion thereof by the rotation of said projection.

45 3. The combination with a shaft and a bearing-box therefor having a cylindrical chamber, of a disk having lateral ribs or wings on one or both of its sides and rigidly supported on the shaft within said chamber and a body of packing liquid in said chamber.

50 4. The combination with a shaft and a disk rigidly supported thereon and provided with lateral ribs or wings, of a chamber in which said disk has clearance-space and a body of liquid in said chamber.

55 5. The combination with a shaft and a bearing-box having a cylindrical chamber, of a disk of less diameter than said chamber and rigidly mounted upon the shaft within the chamber, said disk having lateral ribs or wings and said chamber having a body of packing liquid.

60 6. The combination with a shaft having a disk rigidly mounted thereon, of a chamber

in which said disk is located, a body of liquid in said chamber, an inlet-pipe and an outlet-pipe for said liquid and a relief-valve in the outlet-pipe.

7. The combination with a shaft having a 70 disk provided with lateral ribs or wings, of a cylindrical chamber in which said disk has clearance-space, means for supplying liquid to said chamber and an escape pipe or passage having an automatic relief-valve. 75

8. The combination with a shaft having a circumferentially-grooved disk provided with lateral ribs or wings, of a cylindrical chamber in which said disk has clearance-space, means for supplying packing liquid to the 80 bottom of said chamber and an escape pipe or passage having an automatic relief-valve.

9. The combination with a shaft and a circumferentially-grooved and laterally-ribbed disk rigidly mounted thereon, of a cylindrical 85 chamber in which said disk has clearance-space, means for supplying packing liquid to the bottom of said chamber, an escape pipe or passage connected to the top of the chamber and an automatic relief-valve in said pipe 90 or passage.

10. In a fluid-pressure turbine, the combination with the turbine-shaft and a laterally-ribbed disk rigidly mounted thereon, of a bearing-box having a cylindrical chamber in 95 which said disk has clearance-space, means for supplying packing liquid to the bottom of said chamber, a pipe or passage leading from the top of the chamber, an automatic relief-valve in said pipe or passage and means for 100 adjusting the closing pressure exerted upon said valve.

11. The combination with a rotatable shaft having a disk, of a bearing-box having a chamber for said disk and a body of mobile 105 liquid partially filling said chamber and retained in the outer portion of the chamber by the rotation of the disk.

12. The combination with a shaft having a disk rigidly attached thereto, of a bearing-box having a chamber for said disk in which there are both end and peripheral clearance-spaces and a body of freely-flowing liquid which partially fills said chamber and is retained in the outer portion thereof by the rotation of the disk. 110

13. In a fluid-pressure turbine, the combination with a casing having a bearing-box provided with a cylindrical chamber, of a shaft having a circumferential projection of less length and diameter than said chamber and located therein and a body of liquid partially filling said chamber and retained in the outer portion thereof by the rotation of said projection. 115

14. In a fluid-pressure turbine, the combination with a casing having a bearing-box provided with a cylindrical chamber, of a drum-shaft having a rigidly-mounted disk located in said chamber and a body of liquid 120

partially filling said chamber and retained in the outer portion thereof by the rotation of the disk.

15. A stuffing-box comprising an annular chamber containing a liquid and a disk, the periphery of which extends into said chamber, one of said parts being adapted to be maintained in rapid revolution, whereby the liquid is caused to rotate in said chamber to form a joint between the disk and the chamber.

16. A stuffing-box comprising an annular chamber containing a liquid and a disk, the periphery of which extends into said chamber, one of said parts being provided with projections and adapted to be maintained in rapid revolution, whereby the liquid is caused to rotate in said chamber to form a joint between the disk and the chamber.

20. 17. A stuffing-box comprising an annular chamber containing a liquid and a disk, the periphery of which extends into said chamber, one of said parts being adapted to be maintained in rapid revolution, whereby the liquid is caused to rotate in said chamber to form a joint between the disk and the chamber and a reservoir of liquid connected with said chamber.

25. 18. The combination of a shaft having a projecting collar, with a closure surrounding said collar and means for causing a liquid to rotate in said closure and form a seal by its centrifugal force, between the shaft and the closure-walls, for the purpose specified.

19. A stuffing-box, comprising a fixed part 35 and a part combined with a rotating fluid rotated by said rotating part intervening and forming a joint between said parts.

20. A shaft-packing comprising a casing provided with an annular chamber for receiving a liquid surrounding said shaft, a collar secured to said shaft and extending within said chamber whereby the liquid is caused to rotate in said chamber.

21. The combination in a liquid stuffing- 45 box of a shaft having a collar and a case having an annular recess adapted to retain a liquid under rotation surrounding said collar, with means for causing the liquid to rotate.

22. In a liquid stuffing-box, the combination of the shaft and its collar, with a case-recess inclosing said collar adapted to contain a liquid under high rotation, and projections on said collar for causing said liquid to rotate.

In testimony whereof I have hereunto subscribed my name this 15th day of October, 1903.
